CLAIM

The ornamental design for a gun cabinet bracket, as shown and described.

DESCRIPTION

FIG. 1 is a right front perspective view of a gun cabinet bracket in accordance with the present invention;

FIG. 2 is a front elevation view of the bracket of FIG. 1;

FIG. 3 is a back elevation view of the bracket of FIG. 1;

FIG. 4 is a top view of the bracket of FIG. 1;

FIG. 5 is a bottom view of the bracket of FIG. 1;

FIG. 6 is a left side elevation view of the bracket of FIG. 1;

FIG. 7 is a right side elevation view of the bracket of FIG. 1; and,

FIG. 8 is a left front perspective view of the bracket of FIG. 1, shown with environment.

The broken line showing of a gun cabinet is for the purpose of illustrating environmental structure and forms no part of the claimed design.
